UNITED STATES PATENT OFFICE.

EDWARD WILLIAM ROBERTS, OF WATFORD, AND LOUIS FREDERICK WILLIAM LEES, OF LONDON, ENGLAND.

BUILDING UNIT AND METHOD OF CONSTRUCTING BUILDINGS THEREWITH.

Application filed June 3, 1921 Serial No. 474,699.

(GRANTED UNDER THE PROVISIONS OF THE ACT OF MARCH 3, 1921, 41 STAT. L. 1313.)

To all whom it may concern:

Be it known that we, EDWARD WILLIAM ROBERTS and LOUIS FREDERICK WILLIAM LEES, subjects of the King of the United Kingdom of Great Britain and Ireland, and residents of Watford, England, and London, England, respectively, have invented a certain new and useful Improvement in Building Units and Methods of Constructing Buildings Therewith (for which we have filed application in Great Britain May 21, 1920, Patent No. 169,212), of which the following is a specification.

This invention relates to an improved building element or unit by means of which buildings such as dwelling houses may be rapidly erected, and also to the method of erecting such buildings by means of such improved building units.

The improved unit in accordance with the invention consists of a casting or moulding of a mixture of cement and asbestos or like fibre ordinarily of a length equal to the height between floors of the building to be erected and so shaped as itself or when placed in abutting relation with others to provide inner and outer walls forming cells extending from floor to ceiling which cells may be filled with aggregate or the like the erection thus formed affording a combination of monolithic and sectional construction.

The method of erecting buildings with such units consists in mounting the units on a sill or socket member supported on the foundation, superposing on the cell structure a further sill or socket to act if necessary as a support for superposed units and sills or sockets and filling with aggregate or the like.

The invention is illustrated in the accompanying drawing in which Fig. 1 shows a plan view of one form of the improved building unit with portions of abutting units. Figure 2 shows in plan portions of two building units, one arranged as a corner unit. Fig. 3 is an end elevation of the building unit shown in Fig. 1. Fig. 4 is a sectional elevation of the wall of a house built in accordance with the method and by the units forming the subject of this invention.

As shown in Figs. 1, 2, 3 and 4 of the drawings, in one form the improved building unit consists of a casting or moulding of a mixture of cement and asbestos or like fibre

ordinarily of a length equal to the height between floors of the building to be erected having parallel walled portions *a* united at intervals by transverse walls *b* to form a plurality of cells *a'* and formed along its end faces *a''* or (as shown in Fig. 2) adjacent thereto, in such manner as to abut against a similar unit.

In constructing a building by means of such elements or units there is mounted on or formed as part of the foundation of the building a hollow sill or socket member *d* of asbestos cement or the like formed with openings *d'* of the size of the cells *a'* and shaped to receive the lower faces of the units which are placed thereon, the transverse walls *b* of the units being preferably cut away as indicated at *b'* to fit over the flanges on the socket or sills *d*. On the upper surfaces of these units are placed sills or sockets *c* of suitable length whereupon a mixture of cement and aggregate is poured into the cells, the filling of the sills or socket members *d* and *c* being of fine material the remainder of the filling being preferably such as to leave an air space throughout the lengths of the cells. The sills or sockets *c* are arranged to serve as supports for the joists or the like which may be of U section and are preferably formed of asbestos cement or the like. The units adapted to abut against those

erected are then fitted in place and so on around the foundation, units such as that shown in Fig. 2 being used for corners. The abutting units when in position are so shaped as to form between them pockets *f* extending the length of the units into which cement may be poured, a felt or other sheet *g* or the like being preferably inserted at one end of each pocket to prevent the passage of air or water into the pocket between the abutting edges of the outer walls. As stated these units are ordinarily made to the height corresponding to the usual height between floors of a building, say nine feet, and of a standard width, say of three feet. Where a building of more than one story is to be erected, as indicated in Fig. 4, further units are superposed on the sills or sockets *c*, further sills or sockets *h* are placed thereon and the cells filled with aggregate as before. The sockets *h*, as indicated in Fig. 4, are arranged to support the roof trusses and joists which

again may be of fibro-cement. Naturally sockets such as those *h* would be used in lieu of those *e* if the building were only a single story building.

5 Where a window or like opening is to be provided, as indicated in Fig. 4, the units beneath or above the same will not extend the full length but will be of a length dependent on the size and position of the window opening required.

10 Among the advantages of this mode of construction are the following: The units may be entirely factory made and standardized. When erected the units present a 15 finished surface on the exterior and interior surfaces which may be of any pattern desired, no rendering, plastering or rough casting being required. Constructional strength is obtained firstly by the cellular 20 design of the sections and secondly by the monolithic character of the filling or core. A great saving in labour and improvement in the quality of construction are obtained, while great latitude in design and complete 25 standardization of the parts are afforded. Finally, the whole building with the exception of the floors, doors and the like are fireproof, damp-proof, rot-proof and vermin-proof.

30 We claim:

1. An improved building unit consisting of a casting or moulding of a mixture of

cement and asbestos or like fibre of a length substantially equal to the height between floors of a building, and consisting of parallel walled portions united at uniform intervals by transverse walls to form a plurality of cells extending throughout the length of the unit, the said transverse walls extending at right angles to the parallel walled portions, the walls closing each of the outermost cells being formed with recessed portions to afford in conjunction with other units pockets for the insertion of binding material.

2. An improved building unit consisting of a casting or moulding of a mixture of cement and asbestos or like fibre of a length substantially equal to the height between floors of a building, and consisting of parallel walled portions united at uniform intervals by five transverse walls to form a plurality of cells extending throughout the length of the unit, the said transverse walls extending at right angles to the parallel walled portions, the walls closing each of the outermost cells being formed with recessed portions to afford in conjunction with other units pockets for the insertion of binding material.

In testimony whereof we have signed our names to this specification.

EDWARD WILLIAM ROBERTS.
LOUIS FREDK. WILLIAM LEESE.
